CLAIM

The ornamental design for a protective case as shown and
described.

DESCRIPTION

FIG. 1 is a top, front, and right side axonometric view of a
protective case, showing our new design;
FIG. 2 is a bottom, rear, and left side axonometric view
thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The dashed broken lines in the figures depict portions of the
protective case which form no part of the claimed design.
The dot-dot-dash broken lines in the figures represent the
boundary of the claim, and form no part of the claimed
design.

1 Claim, 8 Drawing Sheets
